[57] CLAIM

The ornamental design for a corner fireplace doors and
panel, as shown and described.

DESCRIPTION

FIG. 1 is a perspective view of a corner fireplace doors and panel, showing my new design;

FIG. 2 is a perspective view thereof, shown with the doors open;

FIG. 3 is a left side elevational view of the device as
shown in FIG. 1;

FIG. 4 is a front elevational view of the device as
shown in FIG. 1;

FIG. 5 is a top plan view, the bottom being a mirror
image thereof;

FIG. 6 is a perspective view shown with the doors opened further than in FIG. 2;

FIG. 7 is a front elevational view of the device as
shown in FIG. 6;

FIG. 8 is a sectional view taken along line 8—8 of FIG.
1;

FIG. 9 is a right side elevational view of the device as
shown in FIG. 1; and

FIG. 10 is a rear elevational view of the device as
shown in FIG. 1.
